Fig. 10

FIG. 1 is a front elevational view of a set of cards for displaying identifying skin condition indicia for cosmetic purposes in closed condition, showing my new design;

FIG. 2 is a rear elevational view thereof;

FIG. 3 is a left end elevational view thereof;

FIG. 4 is a right end elevational view thereof;

FIG. 5 is a top plan view thereof;

FIG. 6 is a bottom view thereof;

FIG. 7 is a perspective view thereof, on an enlarged scale taken from the front and slightly above;

FIG. 8 is a perspective view thereof, on an enlarged scale, taken from the rear and slightly below;

FIG. 9 is a further perspective view thereof taken from the front and slightly above showing the cards in opened position and showing the front faces of the cards upon which can be displayed identifying skin condition indicia; and

FIG. 10 is a further perspective view thereof taken from the rear and slightly below showing the cards in

opened position and showing the view opposite that shown in FIG. 9.

I claim:

The ornamental design for a set of cards for displaying identifying skin condition indicia for cosmetic purposes, substantially as shown and described.
